CLAIM

The ornamental design for a personal effects holder, as shown and described.

DESCRIPTION

FIG. 1 is a front elevational view of a first embodiment of a personal effects holder showing my design;

FIG. 2 is a left side elevational view thereof;

FIG. 3 is a rear elevational view thereof;

FIG. 4 is a rear perspective view thereof;

FIG. 5 is a right side elevational view thereof;

FIG. 6 is a top plan view thereof;

FIG. 7 is a bottom plan view thereof;

FIG. 8 is a first front perspective view thereof;

FIG. 9 is a second front perspective view thereof;

FIG. 10 is a front elevational view thereof including an insert;

FIG. 11 is a front elevation view of a second embodiment of a personal effects holder showing my design;

FIG. 12 is a left side elevational view thereof;

FIG. 13 is a rear elevational view thereof;

FIG. 14 is a rear perspective view thereof;

FIG. 15 is a right side elevational view thereof;

FIG. 16 is a top plan view thereof;

FIG. 17 is a bottom plan view thereof;

FIG. 18 is a first front perspective view thereof;

FIG. 19 is a second front perspective view thereof; and,

FIG. 20 is a front elevational view thereof including an insert.

The broken lines showing an insert in the FIGS. 10 and 20 views show environmental structure associated with the design in a condition of use and form no part of the claimed design.

1 Claim, 20 Drawing Sheets
